CLAIM

The ornamental design for a scooter frame, as shown and described.

DESCRIPTION

FIG. 1 is a front perspective view of the scooter frame of the present invention showing our new design;

FIG. 2 is a front end view thereof;

FIG. 3 is a rear end view thereof;

FIG. 4 is a top plan view thereof;

FIG. 5 is a side elevational view thereof; and,

FIG. 6 is a bottom plan view thereof.
